[57] CLAIM

The ornamental design for a animal exercising run, as shown and described.

DESCRIPTION

FIG. 1 is a top, front and side perspective view of an animal exercising run showing my new design, a cable being shown in dotted lines for the sake of convenience; FIG. 2 is a front elevational view thereof; FIG. 3 is a rear elevational view thereof; FIG. 4 is a side elevational view thereof; FIG. 5 is a side elevational view thereof; FIG. 6 is a top plan view thereof; FIG. 7 is a bottom view thereof; FIG. 8 is a perspective view as seen from the side opposite to FIG. 1; FIG. 9 is a perspective view showing the animal exercising run in a set up condition, with the support posts and grass being shown in dotted lines because they do not form part of the invention; and, FIG. 10 is a perspective view thereof as seen from the side of FIG. 6.
